C. J. JACKSON.
SCREEN ATTACHMENT FOR WINDOWS.
APPLICATION FILED MAY 9, 1914.

Patented Nov. 17, 1914.

Carl J. Jackson,

BY *E. Siggins*

ATTORNEY

UNITED STATES PATENT OFFICE.

CARL JOHAN JACKSON, OF SUPERIOR, WISCONSIN.

SCREEN ATTACHMENT FOR WINDOWS.

1,117,390.

Specification of Letters Patent. Patented Nov. 17, 1914.

Application filed May 9, 1914. Serial No. 837,437.

To all whom it may concern:

Be it known that I, CARL J. JACKSON, a subject of the King of Norway, residing at Superior, in the county of Douglas and State 5 of Wisconsin, have invented a new and useful Screen Attachment for Windows, of which the following is a specification.

The invention relates to a screen attachment for windows.

10 The object of the present invention is to improve the construction of window screens and to provide a simple, practical, and comparatively inexpensive screen attachment designed to be applied to a window at the 15 upper sash and adapted, when the upper sash is lowered for ventilation, to provide a fly exit for causing the flies crawling upward on the sash to pass outward to the exterior of the window.

20 A further object of the invention is to provide a device of this character equipped with means arranged to prevent flies from entering at the exit passage.

With these and other objects in view the 25 invention consists in the construction and novel combination of parts hereinafter fully described, illustrated in the accompanying drawing, and pointed out in the claims here- 30 to appended, it being understood that va- rious changes in the form, proportion, size and minor details of construction, within the scope of the claims, may be resorted to 35 without departing from the spirit or sacrificing any of the advantages of the invention.

In the drawing:—Figure 1 is a front elevation of a screen attachment constructed in accordance with this invention and shown applied to a window. Fig. 2 is a vertical 40 sectional view of the same. Fig. 3 is a horizontal sectional view partly on the line 3—3 of Fig. 2, the section being also taken through one side of the upper sash and the means for slidably connecting the same with 45 the screen. Fig. 4 is a horizontal sectional view on the line 4—4 of Fig. 2. Fig. 5 is a rear perspective view of the screen attachment. Fig. 6 is a detail perspective view of one of the slides. Fig. 7 is a detail view of 50 the spacing strip for offsetting the slide from the sash.

Like numerals of reference designate corresponding parts in all the figures of the drawing.

55 In the accompanying drawing, in which is illustrated the preferred embodiment of

the invention, 1 designates a window screen consisting of a sheet 2 of wire gauze or other screen material, secured within a metallic binding or frame consisting of a horizontal top bar 3 and vertical side bars 4, which are extended below the lower edge of the screen material. The top bar 3 is preferably constructed of a piece of sheet metal folded longitudinally to provide two sides or flanges for embracing the upper edge of the screen material. The side bars 4 are also preferably constructed of sheet metal folded longitudinally to form side flanges for embracing the side edges of the screen material, which is secured between the flanges of the top and side bars by split rivets 5 or other suitable fastening devices. The split rivets 5 pierce the rear flanges of the top and side bars and pass through the screen material and have their legs bent or upset against the front face of the screen material, and arranged between the same and the front flange, which is not perforated by the fastening devices 5. The upper ends of the 80 side bars are arranged between the flanges of the top bar and are secured to the same by fastening devices 6, preferably consisting of split rivets and having their sides or legs bent or upset against the rear flange of the 85 top bar 3. By this construction an inexpensive screen of great strength and durability is provided.

The side bars are constructed of a strip of metal of a width in excess of the width 90 of the strip of metal forming the top bar 3, and the side bars 4 have their outer portions bent inwardly and rearwardly to form longitudinal flanges 7, set at an angle to the plane of the rear flanges of the side bars 4 95 and forming intervening grooves or ways for the reception of slides 8 carried by an upper sash 9. The window screen is provided at the top with projecting lugs or ears 10, consisting of plates or pieces secured to 100 the screen by the said fastening devices 6, and fastened to the window frame or casing at the top thereof by screws 11 or other suitable fastening devices, which are embedded in the top parting strips 12 of the 105 window frame or casing 13. The screen is arranged between the side parting strips 14 and the extended side bars terminate short of the upper edge of the lower sash, as clearly illustrated in Fig. 2 of the drawing. 110

The upper sash 9 is constructed substantially the same as an ordinary upper sash,

with the exception that the top bar 3 is omitted and the glass 15 extends upwardly to the upper ends 16 of the side bars of the said upper sash 9. The upper edge of the glass 15 and the upper ends 16 of the side bars extend above the lower edge of the parting strip 12, being thereby received within the window frame or casing approximately the distance of half an inch. The top of the window frame or casing may also be grooved to receive the upper edge of the glass and the upper ends of the side bars, if desired. The side bars are connected at their lower portions by a transverse brace 17 consisting of a rod arranged exteriorly of the sash and located in rear of the top bar of the lower sash when the said upper sash is lowered for the purpose of ventilation. The slides 8 are preferably constructed of sheet metal folded to provide two plies or thicknesses and bent longitudinally to form an inner attaching portion 18 and an outer engaging portion which is arranged at an obtuse angle to the attaching portion 18. The slides are secured to the side bars of the upper sash by suitable fastening devices, spacing strips 19 being preferably interposed between the attaching portions 18 and the side bars of the sash, as clearly illustrated in Fig. 4 of the drawing. The outer angularly disposed portions of the slides fit in the grooves or ways of the side bars 4 of the screen, and slide therein when the upper sash is raised or lowered. The grooves or ways of the side bars of the screen are closed at their lower ends by stops 20 formed by bending the metal transversely, as clearly illustrated in Fig. 5 of the drawing. This forms a convenient means for limiting the downward movement of the upper sash, so that an inclined strip 21 of the screen may be properly positioned with relation to the upper edge of the sash to form a fly exit. The strip 21, which extends entirely across the space between the side bars of the screen, is suitably secured at its lower edge to the same and it extends upwardly and outwardly to a point nearly over the upper edge of the glass of the upper sash, when the latter is lowered to its ventilating position. The inclined strip is arranged in spaced relation with the upper edge of the glass to permit the flies crawling upward on the glass of the upper sash to pass outward to the exterior of the window, and it is provided at its free edge with projecting wires 22 which extend upwardly at various angles. These projecting wires, while not interfering with the free exit of flies and other insects, assist in forming a barrier to prevent flies from entering the exit passage between the screen and the glass of the upper sash. In practice, when it is desired to cause the flies to pass out through the exit passage, 65. the lower sash is shaded or screened, so that

the glass of the upper sash will attract the insects. By this means the flies will be caused to crawl up the upper sash and escape through the exit passage. The upper sash is designed to be equipped with spring 70 actuated bolts 23 for engaging the window frame or casing to lock the upper sash. These bolts are arranged a sufficient distance above the bottom of the upper sash, so as to be exposed for operation above the 75 lower sash 24 when the said upper sash is lowered. Any other suitable locking means may, of course, be employed for securing the upper sash in its adjustment.

What is claimed is:—

1. A screen attachment including a window screen provided with means for securing it in a fixed position within the top portion of a window frame in advance of the upper sash, and means for slidably connecting the screen with the upper sash, said screen being arranged in spaced relation with the glass of the upper sash to provide a fly exit when the upper sash is lowered. 80
2. A screen attachment including a screen provided with means for securing it in a fixed position within the upper portion of a window frame in advance of the upper sash, said screen being provided at opposite sides with longitudinal grooves or ways 85 and having stops at the lower ends thereof, slides provided with means for mounting them on the upper sash, and movable in the grooves or ways of the screen, the latter being spaced from the glass of the upper sash to provide a fly exit when the said upper sash is lowered, and means located at the fly exit for preventing the return of flies. 90
3. A screen attachment including a screen provided with means for securing it in a fixed position within the upper portion of a window frame or casing in advance of the upper sash, said screen being also provided with side bars having extended lower portions and provided with longitudinal grooves or ways, slides provided with means for securing them to the upper sash and movable in the grooves or ways of the side bars of the screen, the latter being 100 spaced from the glass of the upper sash to provide a fly exit when the upper sash is lowered, and means located at the fly exit for preventing the return of flies. 105
4. A screen attachment including a screen 110 provided with a frame comprising a top bar having attaching means and side bars bent longitudinally to form flanges, said flanges being arranged at the rear face of the screen to form grooves or ways, and the side bars 115 being bent at their lower ends to form stops, and slides movable in the grooves or ways and having means for attaching them to the opposite sides of the upper sash of a window, said slides being spaced from the 120
5. The screen attachment including a screen 125 provided with a frame comprising a top bar having attaching means and side bars bent longitudinally to form flanges, said flanges being arranged at the rear face of the screen to form grooves or ways, and the side bars 130 being bent at their lower ends to form stops, and slides movable in the grooves or ways and having means for attaching them to the opposite sides of the upper sash of a window, said slides being spaced from the 135

- glass of the upper sash to form a fly exit when the upper sash is lowered.
5. The combination of a window provided with an upper sash having its glass extended to the upper ends of the side bars of the sash, a screen provided with means for securing it in a fixed position within the upper portion of the window frame or casing, said screen being spaced from the
- 10 glass of the upper sash to provide a fly exit when the upper sash is lowered, and a transverse strip mounted on the screen at an inclination and arranged to extend over the fly exit to prevent the return of flies.
- 15 6. The combination of a window provided with an upper sash having its glass extended to the upper ends of the side bars

of the sash, a bracing rod extending across the exterior of the upper sash at the lower portion thereof and arranged to be concealed by the top bar of the lower sash when the said upper sash is lowered, and a screen mounted in a fixed position within the upper portion of the window in spaced relation with the glass of the upper sash to 20 form a fly exit.

In testimony, that I claim the foregoing as my own, I have hereto affixed my signature in the presence of two witnesses.

CARL JOHAN JACKSON.
